UNITED STATES PATENT OFFICE.

CHARLES MORGAN AND MATHIAS REDLINGER, JR., OF FREEPORT, ILLINOIS, ASSIGNORS TO SAID CHARLES MORGAN, EDGAR H. MORGAN, AND ALBERT BAUMGARTEN, OF SAME PLACE.

DESIGN FOR A BOX FOR COFFEE-MILLS.

SPECIFICATION forming part of Design No. 21,619, dated June 7, 1892.

Application filed February 27, 1892. Serial No. 423,090. Term of patent 7 years.

To all whom it may concern:

Be it known that we, CHARLES MORGAN and MATHIAS REDLINGER, Jr., citizens of the United States, residing at Freeport, in the county of Stevenson and State of Illinois, have invented and produced a new and original Design for a Box for a Coffee-Mill, of which the following is a specification, reference being had to the accompanying drawing, which is 10 a perspective view of a coffee-mill box constructed in accordance with our design.

In the drawing, A is the front wall or face of an approximately rectangular box having side walls A', top A², a suitable bottom, and 15 a back piece A³ of slightly greater width than

the box and projecting considerably above and below it. The top piece A² of the box is slightly inclined downward from rear to front, as shown, and is provided with an ornamental cap B.

What we claim as new, and desire to secure by Letters Patent, is—

The design for a box for a coffee-mill, substantially as shown and described.

CHARLES MORGAN.
